CLAIM

The ornamental design for a squeeze bottle for food products, as shown and described.

DESCRIPTION

FIG. 1 is a front elevational view showing our new design, the rear elevational view being substantially identical thereto, except for the screw threads;

FIG. 2 is a right side elevational view thereof, the left elevation being substantially identical thereto, except for the screw threads; and,

FIG. 3 is a top plan view thereof.

1 Claim, 2 Drawing Sheets**FIG. 1**

FIG. 2

FIG. 3
